UNITED STATES PATENT OFFICE.

OTTO N. MUELLER, OF INDIANAPOLIS, INDIANA.

REINFORCING CONCRETE.

No. 876,480.

Specification of Letters Patent

Patented Jan. 14, 1908.

Application filed November 15, 1906. Serial No. 343,645.

To all whom it may concern:

Be it known that I, OTTO N. MUELLER, a citizen of the United States, residing at Indianapolis, in the county of Marion and State 5 of Indiana, have invented certain new and useful Improvements in Reinforcing Concrete, of which the following is a specification.

The object of my invention is to produce a 10 reinforced concrete structure wherein the floors are so reinforced and connected to the columns that there need be either no beams at all between the columns, or if beams be used, they may be of the same or less depth 15 than the thickness of the floor, thus making it possible to produce an extended smooth ceiling uninterrupted by depending beams or enlarged upper ends of supporting columns.

The accompanying drawings illustrate my 20 invention:

Figure 1 is a horizontal section of a portion of a building, with my improved floor reinforcement arranged in connection with a metal skeleton ready to receive the concrete. Fig. 2 a vertical section after the concrete has been laid; Fig. 3 a horizontal section of a reinforced concrete structure with the floor reinforcement arranged to receive the concrete in accordance with my invention; Fig. 4 a vertical section through a column and adjacent floor portions; Fig. 5 a detail of a slight modification.

In Figs. 1 and 2, 10 indicates vertical columns of any desired construction connected 35 by light beams 11 preferably of less depth than the thickness of the floors. Laid around each column and radiating therefrom across the space between that column and the adjacent columns are light reinforcing rods 12. 40 In erection, a flat centering is provided to support the concrete of the floor square, and the radiating ends of the reinforcing rods 12 are extended promiscuously across the square, their ends being free and no particular attention being paid to the exact arrangement of the radiating rods, the only care necessary being to distribute the rods fairly evenly over the entire square. If desired, adjacent the outer walls, some of the rods 12, 45 which are like rods 12, may be anchored to the light connecting beams 11 instead of being directly wrapped around the columns. Also the radiating ends may be hooked over the tie beams, if so desired, to aid in erection. 50 The concrete 13 is then spread over the centering so as to embed the overlapping rein-

forcing rods 12. Portions of the lower course of rods 12 *i. e.*, those which lie immediately upon the centering, will be exposed upon the ceiling but these become covered 60 when the plastering 14 is applied. This may be overcome by hooking the radiating end over the tie beams so as to raise the rods sufficiently to place concrete under them.

In Figs. 3 and 4 the columns 100 are of the 65 desired reinforced concrete construction and in connection with such a structure I prefer to use a reinforcing unit consisting of a bundle of rods 112 bound together for a very short distance at their middles. To begin 70 with, the rods of each bundle lie close together throughout their length and the bundle may be easily threaded through the reinforcement of the columns 100 before the concrete is applied and the ends then separated 75 and spread so as to be distributed over the square between adjacent columns. The concrete 113 is then applied in the usual well known manner, so that the floors and columns become an integral structure. In this 80 construction it is advisable to provide tension reinforcing members 115 extending directly between adjacent columns. I also deem it advisable to thread the rods 112 through the column reinforcement at a point 85 slightly above the upper face of the finished floor square, as shown in Fig. 4, so that the radiating ends of the rods 112 will curve downward into the floor-square.

As previously stated, by this construction 90 I am able to produce a very strong floor without the use of beams between the columns of a depth greater than the desired thickness of the floor.

I claim as my invention:

1. In a reinforced concrete structure, the combination, with a plurality of separated concrete columns, and the vertical reinforcement therein, of a set of reinforcing members embedded in a column and principally supported thereby, the ends of said set of reinforcing members being separated so as to radiate from the column support across the adjacent floor square to substantially all parts thereof, and a concrete floor square embedding and supported by said radiated ends.

2. In a reinforced concrete structure, a concrete floor square having a plurality of sets of reinforcing members embedded therein, the said reinforcing members of each set being concentrated at one point in their length

and principally supported at or near the point of concentration while the ends of said reinforcing members are separated so as to diverge from the point of concentration into various portions of the floor square.

3. In a reinforced concrete structure, a concrete floor square having a plurality of sets of reinforcing members embedded therein, the said reinforcing members of each set being concentrated at one point in their length and principally supported at or near the point of concentration while the ends of

said reinforcing members are separated so as to diverge from the point of concentration into various portions of the floor square, the 15 said separated ends being unconnected.

In witness whereof I have hereunto set my hand and seal at Indianapolis, Indiana, this 10th day of November A. D., one thousand nine hundred and six.

OTTO N. MUELLER. [L. s.]
Witnesses:

ARTHUR M. HOOD,
THOMAS W. MCMEANS.
